CLAIM

The ornamental design for a makeup application device, as shown and described.

DESCRIPTION

FIG. 1 is a frontal perspective view of the makeup application device;

FIG. 2 is rearward perspective view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a bottom plan view thereof; and,

FIG. 8 is a top plan view thereof.

The dashed lines are for illustration of environmental subject matter only and form no part of the claimed design.
